Patented Dec. 13, 1966

206,461

PORTABLE PHONOGRAPH OR SIMILAR ARTICLE

David Chapman and Marlan Polhemus, Chicago, Ill., as-
signors to Radio Corporation of America, a corporation
of Delaware

Filed May 28, 1965, Ser. No. 85,512

Term of patent 14 years

(Cl. D56—4)

Fig. 1.

Fig. 2.

*Fig. 3.**Fig. 4.**Fig. 5.*

FIG. 1 is a front perspective view of a portable phonograph or similar article embodying our new design in its closed position;

FIG. 2 is a front perspective view of the phonograph shown in its open position;

FIG. 3 is a top plan view of FIG. 1;

FIG. 4 is a side elevational view of FIG. 1, the opposite side being substantially a mirror image thereof; and

FIG. 5 is a rear elevational view of FIG. 1.

The dominant features of this design reside in the portions shown in full lines. The bottom of the turntable housing in FIG. 2 forms the back of the phonograph when the housing is swung 90° on the pins by which it is attached to the vertical posts, while the backs of the loudspeaker housings in FIG. 2 form the front of the phonograph when the housings are swung forward on the vertical hinges by which they are attached to the vertical posts.

We claim:

The ornamental design for a portable phonograph or similar article, substantially as shown and described.
